(57) **CLAIM**

We claim the ornamental design for a utility connection station, as shown and described.

DESCRIPTION

FIG. 1 is a front perspective view of the claimed design according to an exemplary embodiment;

FIG. 2 is a front elevation view of the claimed design of FIG. 1;

FIG. 3 is a rear elevation view of the claimed design of FIG. 1;

FIG. 4 is a top view of the claimed design of FIG. 1;

FIG. 5 is a bottom view of the claimed design of FIG. 1;

FIG. 6 is a right side elevation view of the claimed design of FIG. 1; and,

FIG. 7 is a left side elevation view of the claimed design of FIG. 1.

The ornamental design which is claimed is shown in solid lines in the drawings. The broken lines in the drawings are for illustrative purposes only and form no part of the claimed design.
